(57) **CLAIM**

The design for a popliteal open/closed knee brace, as shown and described.

DESCRIPTION

FIG. 1 is a front view of a first embodiment of the popliteal open/closed knee brace, showing the new design;

FIG. 2 is a left side view of the popliteal open/closed knee brace;

FIG. 3 is a rear view thereof;

FIG. 4 is a right side view thereof; and,

FIG. 5 is a right front perspective view thereof.

The broken line showing of a leg is for the purpose of illustrating environment that forms no part of the claimed design.
